DWIGHT BRUCE KENNEDY, OF OAKMONT, PENNSYLVANIA.

DESIGN FOR A CAR-TRUCK FRAME.

SPECIFICATION forming part of Design No. 29,028, dated July 12, 1898.

Application filed May 16, 1898. Serial No. 680,881. Term of patent 7 years.

To all whom it may concern:

Be it known that I, DWIGHT BRUCE KENNEDY, a citizen of the United States, residing in the borough of Oakmont, county of Allegheny, and State of Pennsylvania, have invented a new and useful Design for Car-Truck Frames, of which the following is a specification.

In order that the essential and novel features of said design may be clearly understood, it will be necessary to describe the same in detail in connection with the accompanying drawing.

Said drawing represents a perspective view of a car-truck frame embodying my novel design.

A car-truck frame embodying my novel design embraces two parallel side members and transverse transom members extending between said side members and intersecting the same midway between their ends. Said transom members consist of rolled channel-sections arranged in vertical planes and having their longitudinal flanges directed outwardly. Vertical plates arranged at right angles to the side members extend between the opposite ends thereof, giving the appearance to said parts of a parallelopiped open on two of its opposite sides. Two rectangular plates extend between the upper edges of the transom members in horizontal planes; one overlying the other, the upper one being narrower than the lower one, thereby forming an offset on the sides adjacent to the side members and having in its center a raised circular figure having a central concave depression.

The upper or compression member of each of the side members is formed of an angle-bar, one web of which is directed outwardly. Said compression member extends equidistant on each side of the transom members and rises therefrom on graceful lines and terminates at each end below the plane of the middle portion thereof, giving to said ends a hooked shape, the portions of said member adjacent to its opposite ends being arranged in vertical planes. The angle-bar forming the tension member of each of the side members is arranged inside of said compression member, with one of its webs directed inwardly, and is parallel at its opposite ends with the hooked portions of said compression members, said tension and compression members converging from each side of said transom members and intersecting in planes above the intermediate portion of the compression members, with their outer ends arranged side by side in hooked form and with the outer surfaces of their laterally-directed webs at each end of each side member arranged in the

member to the highest points of the latter, from which it is curved downwardly, with its middle portion below the transom members. 55 The effect of this arrangement presents to the eye a broad outwardly-facing vertical surface at each end of each of the side members which is formed by the laterally-directed webs of the tension and compression members, which 60 surface curves gracefully inward toward the transom members to the highest points of the side members, at which points said compression and tension members diverge, said vertical and inwardly-curved surfaces being 65 broken by intervening spaces, as shown. A plate overlies the middle portion of the compression member and the adjacent ends of the transom members, said plate conforming to the curvature of said compression member and terminating at its opposite ends at the inwardly-curved surfaces of the tension and compression members. Said plate is widest at its middle portion and tapers gradually at one edge thereof toward its opposite 70 ends. On the opposite sides of said transom members and adjacent to the intersection of the compression and tension members depending plates are arranged in a plane parallel with the plane of said compression members, which extend at their lower ends to an angle-bar located transversely below the transom members and parallel with the compression member. U-shaped angle-bars constituting the pedestals and having their parallel members in vertical planes are arranged between the vertical end portions of the compression and tension members and the depending plates 80 on each end of the side members. The vertical portions of said bars on each side of each of the pedestals have their laterally-directed webs in the same plane, forming oppositely-arranged broad parallel surfaces interrupted by an intervening space, which 85 are connected at their upper ends by a transverse curved surface, and with their other webs in planes parallel with the planes of the inwardly-directed flanges of the compression and tension members and said depending 90 plates. A cross-piece extends between the lower open ends of said U-shaped pedestal bars.

The characteristic feature of my design consists in the shape and general aspect of the angle tension and compression members having oppositely-arranged flanges or webs and arranged at their intermediate portions horizontally above and below the transom members, said tension and compression members converging from each side of said transom members and intersecting in planes above the intermediate portion of the compression members, with their outer ends arranged side by side in hooked form and with the outer surfaces of their laterally-directed webs at each end of each side member arranged in the

I claim as my design—

The design for a car-truck frame, substantially as shown and described.

DWIGHT BRUCE KENNEDY.
